CLAIM

The ornamental design for a camera, as shown and described.

DESCRIPTION

FIG. 1 is a front elevation view of a camera showing our new design with an environmental image of a fragmentary human hand disclosed in broken lines;

FIG. 2 is a top and rear perspective view thereof, shown with the handheld portion omitted for ease of illustration;

FIG. 3 is a top and front perspective view thereof;

FIG. 4 is a front perspective view thereof, shown with the camera lens portion omitted for ease of illustration; and,

FIG. 5 is a rear perspective view thereof.

The broken lines depict portions of the camera that form no part of the claimed design. The broken lines showing a human hand in FIG. 1 represent environmental structure and form no part of the claimed design. Additionally, the dash-dot lines denote the boundary of the claim and form no part of the claimed design.
